CLAIM

The ornamental design for a portion of volute casing for a pump, as shown and described.

DESCRIPTION

FIG. 1 is a perspective view of a portion of volute casing for a pump in accordance with our new design;
 FIG. 2 is a first side elevational view of the portion of volute casing for a pump illustrated in FIG. 1;
 FIG. 3 is a second side elevational view of the portion of volute casing for a pump illustrated in FIG. 1;
 FIG. 4 is a first end elevational view of the portion of volute casing for a pump illustrated in FIG. 1;
 FIG. 5 is a second end elevational view of the portion of volute casing for a pump illustrated in FIG. 1;
 FIG. 6 is a bottom plan view of the portion of volute casing for a pump illustrated in FIG. 1;
 FIG. 7 is a top plan view of the portion of volute casing for a pump illustrated in FIG. 1;
 FIG. 8 is a perspective view of a portion of volute casing for a pump in accordance with our new design;
 FIG. 9 is a first side elevational view of the portion of volute casing for a pump illustrated in FIG. 8;
 FIG. 10 is a second side elevational view of the portion of volute casing for a pump illustrated in FIG. 8;
 FIG. 11 is a first end elevational view of the portion of volute casing for a pump illustrated in FIG. 8;
 FIG. 12 is a second end elevational view of the portion of volute casing for a pump illustrated in FIG. 8;
 FIG. 13 is a bottom plan view of the portion of volute casing for a pump illustrated in FIG. 8;
 FIG. 14 is a top plan view of the portion of volute casing for a pump illustrated in FIG. 8;
 FIG. 15 is a perspective view of a portion of volute casing for a pump in accordance with our new design;

FIG. 16 is a first side elevational view of the portion of volute casing for a pump illustrated in FIG. 15;
 FIG. 17 is a second side elevational view of the portion of volute casing for a pump illustrated in FIG. 15;
 FIG. 18 is a first end elevational view of the portion of volute casing for a pump illustrated in FIG. 15;
 FIG. 19 is a second end elevational view of the portion of volute casing for a pump illustrated in FIG. 15;
 FIG. 20 is a bottom plan view of the portion of volute casing for a pump illustrated in FIG. 15;
 FIG. 21 is a top plan view of the portion of volute casing for a pump illustrated in FIG. 15;
 FIG. 22 is a perspective view of a portion of volute casing for a pump in accordance with our new design;
 FIG. 23 is a first side elevational view of the portion of volute casing for a pump illustrated in FIG. 22;
 FIG. 24 is a second side elevational view of the portion of volute casing for a pump illustrated in FIG. 22;
 FIG. 25 is a first end elevational view of the portion of volute casing for a pump illustrated in FIG. 22;
 FIG. 26 is a second end elevational view of the portion of volute casing for a pump illustrated in FIG. 22;
 FIG. 27 is a bottom plan view of the portion of volute casing for a pump illustrated in FIG. 22;
 FIG. 28 is a top plan view of the portion of volute casing for a pump illustrated in FIG. 22;
 FIG. 29 is a perspective view of a portion of volute casing for a pump in accordance with our new design;
 FIG. 30 is a first side elevational view of the portion of volute casing for a pump illustrated in FIG. 29;
 FIG. 31 is a second side elevational view of the portion of volute casing for a pump illustrated in FIG. 29;
 FIG. 32 is a first end elevational view of the portion of volute casing for a pump illustrated in FIG. 29;
 FIG. 33 is a second end elevational view of the portion of volute casing for a pump illustrated in FIG. 29;
 FIG. 34 is a bottom plan view of the portion of volute casing for a pump illustrated in FIG. 29;
 FIG. 35 is a top plan view of the portion of volute casing for a pump illustrated in FIG. 29;
 FIG. 36 is a perspective view of a portion of volute casing for a pump in accordance with our new design;
 FIG. 37 is a first side elevational view of the portion of volute casing for a pump illustrated in FIG. 36;
 FIG. 38 is a second side elevational view of the portion of volute casing for a pump illustrated in FIG. 36;
 FIG. 39 is a first end elevational view of the portion of volute casing for a pump illustrated in FIG. 36;
 FIG. 40 is a second end elevational view of the portion of volute casing for a pump illustrated in FIG. 36;
 FIG. 41 is a bottom plan view of the portion of volute casing for a pump illustrated in FIG. 36;
 FIG. 42 is a top plan view of the portion of volute casing for a pump illustrated in FIG. 36;
 FIG. 43 is a perspective view of a portion of volute casing for a pump in accordance with our new design;
 FIG. 44 is a first side elevational view of the portion of volute casing for a pump illustrated in FIG. 43;
 FIG. 45 is a second side elevational view of the portion of volute casing for a pump illustrated in FIG. 43;
 FIG. 46 is a first end elevational view of the portion of volute casing for a pump illustrated in FIG. 43;
 FIG. 47 is a second end elevational view of the portion of volute casing for a pump illustrated in FIG. 43;

FIG. 48 is a bottom plan view of the portion of volute casing for a pump illustrated in FIG. 43; and,

FIG. 49 is a top plan view of the portion of volute casing for a pump illustrated in FIG. 43.

The broken lines shown in FIGS. 1-49 illustrate portions of the portion of volute casing for a pump that form no part of the claimed design.
